UNITED STATES PATENT OFFICE.

CHARLES R. GREUTER, OF WILKES-BARRE, PENNSYLVANIA.

MULTIPLE CARBURETER.

No. 879,380.

Specification of Letters Patent.

Patented Feb. 18, 1908.

Application filed February 25, 1907. Serial No. 359,279.

To all whom it may concern:

Be it known that I, CHARLES R. GREUTER, a citizen of the United States of America, residing at Wilkes-Barre, Pennsylvania, have 5 invented new and useful Improvements in Multiple Carbureters, of which the following is a specification.

This invention relates to an improved carbureter of the multiple type designed to provide means for permitting the throttling of 10 the explosive mixture and at the same time maintain the proper proportion of air and oil, whereby a variable quantity of explosive mixture may be introduced into the motor 15 according to the needs thereof without changing the proper proportion of the two elements of the mixture.

To this end the present invention primarily contemplates an improvement in the 20 multiple type or carbureters or vaporizers whereby certain of the oil spray tubes are effectually closed or cut off when the vents communicating therewith are closed.

In other words the present invention has 25 in view, as a principal object thereof, the provision of a simple and practical form of automatic cut off device for certain of the oil spray tubes, so that when the same are not intended to be in action the outlet of oil or 30 vapor therefrom is stopped or cut off. This is of essential importance for the reason that heretofore in the multiple type of carbureters or vaporizers the spray tubes or jets which were not supposed to be in action, 35 have been more or less acted upon by the suction of the engine with the result of causing such spray tubes to overflow and waste a large amount of gasoline. This is entirely obviated through the present invention by 40 equipping what may be termed the supplemental individual vaporizers with an automatic cut-off or stopper for the spray tube thereof.

With these and many other objects in view 45 which will more readily appear as the nature of the invention is better understood, the same consists in the novel construction, combination, and arrangement of parts herein-after more fully described, illustrated and 50 claimed.

The essential features of the invention involved in carrying out the objects above indicated are necessarily susceptible to structural modification without departing from 55 the spirit or scope of the invention, but a pre-

ferred embodiment thereof is shown in the accompanying drawings, in which:

Figure 1 is a side elevation of a multiple carbureter embodying the present invention. Fig. 2 is a top plan view thereof. Fig. 3 is a horizontal sectional view on the line 3—3 of Fig. 1. Fig. 4 is an end elevation of the carbureter. Fig. 5 is a vertical sectional view through the primary individual vaporizer, the line of section being on the line 5—5 of Fig. 4. Fig. 6 is a similar view on the line 6—6 of Fig. 4. Fig. 7 is a similar view on the line 7—7 of Fig. 4.

Like references designate corresponding parts in the several figures of the drawings.

The present invention embodies in its general organization a vaporizer body designated in its entirety by the reference character 1, and which essentially comprises a cylindrical valve casing 2 and a plurality or 75 series of individual vaporizers arranged at the side of the valve casing, and designated respectively by the reference characters A, B, and C, the vaporizer A constituting what may be termed a primary vaporizer which is 80 always first thrown into action and used with or without the other vaporizers, while said latter vaporizers constitute what may be characterized as supplemental individual vaporizers which are brought into play ac- 85 cording to the quantity of mixture which is needed for the engine. The several vaporizers A, B, and C are arranged in a series, and are of duplicate construction, as each of the same consists of a mixing tube 3 and an 90 oil spray tube 4 projecting into the mixing tube 3 within one end thereof and provided in its inner end with a jet orifice 5 while the outer end of each oil spray tube is coupled to and projects within an oil supply pipe 6 ar- 95 ranged exterior to the vaporizer body and connected with the usual source of supply for the hydro-carbon. The lower end of each oil spray tube 5 within the oil supply pipe 6 has associated therewith the valve 100 point 7 of a needle controlling valve 8 sub- serving the usual functions in connection therewith for regulating the flow of hydro-carbon through the tube 4 to the jet orifice 5 thereof.

In carrying out the present invention, it is preferable to associate with the oil supply pipe 6, a pipe connection 9 with a float valve chamber 10 of well known construction and function and which is designed to keep the 110

level of the liquid hydro-carbon up to or about the line L indicated on the drawings, which line is in a plane just below the plane of the orifices 5, thereby holding the hydro-carbon or oil at a level where it is easily drawn out by the air suction and vaporized thereby in the mixing tube 3.

The mixing tube 3 for the vaporizer A pierces the side of the cylindrical valve casting 2 through the feeding port 11, the tube 3 for the vaporizer B through the feeding port 12, and the tube 3 for the vaporizer C through the feeding port 13, and all of these several ports are designed to be covered and uncovered by the tubular throttle valve 15. This valve is of a hollow cylindrical form, being open at one end to provide air circulation therethrough and the interior sides of which constitute a circulating chamber 16 which is in communication with a series of venting ports 17, 18, and 19, which are successively of different sizes and respectively coöperate with the feeding ports 11, 12, and 13 for the several vaporizers A, B, and C.

The tubular throttle valve 15 has a journal fit within the base of the valve casing 1 and has attached to its closed end a valve spindle 20 mounted in a bearing 21 provided at one end of the casing 1 and having connected to its outer extremity a rocker arm 22 coöperating with an adjustable stop screw 23 and also having connected therewith an operating rod 23^a leading to the steering wheel control. The said throttle valve is also controlled from a suitable foot controlled connection 24 having a rack section 25 meshing with a gear section 26 on the body of the valve 15.

A distinctive and prominent feature of the present invention resides in associating with the oil spray tube 4 of each supplemental vaporizer B and C a cut-off or stoppering device which essentially consists of a cut-off stopper or stopper pin 27, slidably mounted in a guide bearing 28 formed in the vaporizer body in the longitudinal plane of said oil spray tube 4, and automatically controlled operating means for said stopper pin. In the preferable form of the invention, the automatically controlled operating means for the stopper pin 27 comprise a rocking operating lever 29 pivotally mounted intermediate its ends, as at 31, upon a bearing support 32 on the valve casing 2 and carrying at one end an adjustably mounted inwardly projecting tappet 33, and at its opposite end provided with a fork 34 loosely embracing the outer end of the stopper pin 27 between the adjustable head nut 34^a of said pin and a buffer spring 35 mounted on the said pin. At the pivotal support 31 of each rocking operating lever 29 is arranged an opening or retracting spring 36 coiled about the pivotal support for the operating lever and having its separate spring arms 37 and 38 respectively en-

gaged with a fixed abutment and with the end of the lever 29 which is connected with the reciprocal stopper pin 27. The tension of the said spring 36 is exerted in a direction to provide for normally lifting or retracting the stopper pin in a direction away from the oil spray tube with which it coöperates.

The inwardly projecting tappet 33 at one end of each rocking operating lever 29 operates through an opening 39 in the wall of the casing 2, and is adapted to be engaged by the peripheral surface of the throttle valve 15 and also to drop into a clearance channel or recess 40 provided for its reception in the surface of the throttle valve body.

The cut-off or stopper equipment for each of the vaporizers B and C is exactly the same and the action is the same. However, in this connection, it will be observed that the said cut-off or stopper devices for each of the supplemental vaporizers are so arranged that the passage of the hydro-carbon through the tubes 4 is entirely cut-off and sealed from the influence of the engine suction when the venting ports 18 and 19 for said vaporizers are closed. It will be observed that the cut-off or stopper device for each vaporizer B and C has the stopper pin thereof arranged in axial alinement with the oil spray tube 4 and is adapted to close directly over the spray jet or jet orifice 5 of said tube when the throttle valve is turned to a position for closing the venting port therein, which brings the main cylindrical surface of the valve against the tappet 33 and cams the same outward. When the throttle valve is turned to bring the venting ports 18 and 19 into communication with the mixing tubes of the vaporizers B and C, the clearance channels or recesses 40 are brought beneath the tappets 33 so that the springs 36 are free to retract the stopper pins and lift the same to positions uncovering the spray tubes with which they coöperate. In the general operation of the carburetor, it will be understood by those familiar with the art that the valve 15 is turned to first throw the vaporizer A into action and afterwards vaporizer B, and finally vaporizer C, during which operation vaporizer A remains wide open while B and C are thrown into action, and B remaining wide open while C is thrown into action.

This construction also necessarily admits of a wide range of adjustment to permit varying quantities of the explosive mixture to pass to the engine, while at all times there is maintained a proper proportion between the two elements of the mixture by reason of the fact that the feed of liquid and air increases proportionately upon the progressive movement of the valve to open the several ports 17, 18, and 19 and vice versa.

By reference to Fig. 3 of the drawings the circulation of the air and hydrocarbon through the vaporizers and to the engine will

be apparent. Referring to said figure it will be observed that the air is taken in through the outer ends of said vaporizers and carried to the hydrocarbon admission valves, at 5 which point the air and hydrocarbon commingles, and from thence it enters and passes through the chamber 16, to the engine, it being understood that any suitable or preferred pipe coupling may be employed which will provide a proper pipe connection with the outer 10 open end portion of the casing of the valve 15.

I claim:—

1. A carbureter comprising a plurality of vaporizers, a single throttle common to the 15 several vaporizers, and separate cut-offs for the oil feed for certain of the vaporizers, said cut-offs being operated by the throttle.
2. A carbureter comprising a plurality of vaporizers each consisting of a mixing tube and an oil spray tube entering the latter, a 20 single throttle, cut-offs arranged to stopper certain of the oil spray tubes, and means for operating said cut-offs from the throttle.
3. A carbureter comprising a plurality of vaporizers, a throttle common to the several 25 vaporizers, and cut-off devices for the oil feed for certain of the vaporizers and arranged to cut off the oil flow when the vaporizers are throttled.
4. In a carbureter comprising a plurality of vaporizers each consisting of a mixing tube and an oil spray tube in the latter, a 30 rotary throttle valve common to the several vaporizers, and cut-off devices coöperating with certain of the vaporizers, each of said 35 cut-off devices having a stopper movable over the orifice of the spray tube and an operating lever movable in one direction by the throttle valve.

5. A carbureter comprising a plurality of vaporizers each consisting of a mixing tube 40 and an oil spray tube in the latter, a rotary throttle valve common to the several vaporizers, and cut-off devices for certain of the vaporizers, each of said cut-off devices consisting of a reciprocating stopper movable 45 over the orifice of a spray tube, and a spring retracted operating lever connected at one end with the stopper and at its other end having a cam engagement with the throttle valve. 50

6. A carbureter comprising a valve casing, a mixing tube in communication with said casing, an oil spray tube entering the mixing tube, a tubular rotary throttle valve mounted in the casing and having a venting port 55 and also provided in its surface with a clearance recess, and cut-off device consisting of a reciprocating stopper pin working in the mixing tube over the oil spray tube, a rocking operating lever having an operative connection at one end with said stopper and carrying at its opposite end a tappet having an operating engagement with the throttle valve and also adapted to drop into said clearance recess, and a retracting spring arranged to 60 normally rock the lever in one direction and hold the cut-off device in an open position. 65

In testimony whereof, I have signed my name to this specification in the presence of two subscribing witnesses, this 20th day of 70 February 1907.

CHARLES R. GREUTER.
